UNITED STATES PATENT OFFICE

EDWIN C. SPENCE, OF SEATTLE, WASHINGTON.

TOBACCO-BOX.

1,178,548.

Specification of Letters Patent. Patented Apr. 11, 1916.

Application filed October 24, 1914. Serial No. 868,366.

To all whom it may concern:

Be it known that I, EDWIN C. SPENCE, a citizen of the United States, and a resident of Seattle, in the county of King and State 5 of Washington, have invented certain new and useful Improvements in Tobacco-Boxes, of which the following is a true and exact specification.

My invention relates to tobacco boxes, and 10 has for its principal object to provide a receptacle or box, having a spring actuated lid, into which a sack of tobacco will fit snugly, it being understood that the box is made in sizes suitable for the usual one 15 ounce and larger sacks; to provide a receptacle of the above description which is provided with means for releasing the spring cover by using only the thumb or finger of the hand in which the box is held, thereby 20 leaving the other hand free to hold the pipe or cigarette papers into which it is desired to pour the tobacco.

A further object is to provide removable or hinged means for holding the mouth of 25 the tobacco sack open and against the sides of the box.

By the use of the herein described tobacco box, the tobacco is not removed from the original package as purchased, is kept in a 30 dry and sanitary condition at all times, is not allowed to be wasted by spilling from the mouth of the sack, as is usual with the sack as in general use, having a puckering string for closing said sack; is prevented 35 from becoming crushed and ground fine by being carried in the pocket without any protecting casing or box.

Other objects will appear as my invention is more fully described in the following 40 specification, illustrated in the accompanying drawings, and pointed out in the appended claims.

In the drawings, Figure 1 is a side elevation of my device with parts broken away.

Fig. 2 is a plan view with parts broken away. Fig. 3 is a detail of a cover hinge.

Referring more particularly to the drawings, numeral 1 designates a box, of substantially the shape shown, having a cover 2. 50 The box 1 and cover 2 are connected together by a hinge pin 3 which is provided with a spring 4, the inherent energy of

which tends to throw the cover open. The cover 2 is held closed by means of a spring latch 4^a attached thereto, and having an 55 outwardly sloping shoulder 5 which, when the cover is closed, fits into a slot 6 in the box 1. The cover 2 is also provided with a small 60 projecting knob 7. When it is desired to open the box, an upward pressure of the thumb or finger upon the knob 7 is sufficient to release the latch shoulder 5 from engagement with the slot 6, thereby allowing the cover to fly open under the influence of spring 4. A spring sack retainer and spreader 8, 65 which is in the form of an open rectangle of substantially the same dimensions as the inside of the box 1, retains the mouth of a sack 9 against the sides of box 1, and also spreads the mouth of the sack. The function of the 70 member 8 is to hold the sack mouth snugly against the inside of the box 1, thereby preventing the sack 9 from falling out of the box 1, when the latter is tipped to pour its contents out upon a cigarette paper or into 75 a pipe, and also to prevent the mouth of the sack from collapsing during such operation, which of course is liable to occur unless the sack be entirely full. The sack retainer and spreader 8 is easily removable and is so removed when the sack within the box is 80 empty of tobacco, thereby allowing said sack to be removed and a full sack put in place of the empty one. The retainer is then again replaced.

While I am aware that many forms of tobacco boxes are common, yet the objects attained as above outlined are believed to be new.

It is obvious that many minor changes in 90 construction and operation will suggest themselves to anyone skilled in the art, and I therefore do not wish to be limited to the exact form and construction shown.

Having thus described my invention, what 95 I claim as new and desire to protect by Letters Patent, is—

1. In an article of the class described, the combination of a box adapted to hold a sack of tobacco, spring means for holding a tobacco sack against the inside of said box and for also preventing the collapsing of the mouth of the sack.
2. In an article of the class described, the

combination of a box having a smooth and uniform outer surface with means for holding a filled sack against the inside of the box and for also holding the mouth of the sack against collapsing despite an almost empty condition of the sack, said means including a removable, open joint flat spring

of substantially the same size as the inside of the box.

EDWIN C. SPENCE.
